UNITED STATES PATENT OFFICE.

WALTER AIKEN, OF FRANKLIN, NEW HAMPSHIRE.

IMPROVEMENT IN NEEDLES FOR KNITTING-MACHINES.

Specification forming part of Letters Patent No. 78,506, dated June 2, 1868.

To all whom it may concern:

Be it known that I, WALTER AIKEN, of Franklin, in the county of Merrimac and State of New Hampshire, have invented a new and useful Improvement in Knitting-Machine Needles; and I do hereby declare the same to be fully described in the following specification, and represented in the accompanying drawings, marked Figure 1, which is a side view of a needle constructed in accordance with my improvement.

In carrying out my invention I make that portion of the shank of the needle which is in rear of the impelling projection with corrugations arranged in the plane of the said projection, the same being as represented at *a a a*, &c., in the said drawings, in which *A* denotes the shank of the needle, *B* the impelling projection, *C* the hook, and *D* the hook closer or latch.

Fig. 2 exhibits the common movement of making a needle—viz., with what may be termed a “folded” or “doubled” shank—that is, with a portion, *c*, of the shank bent or folded down upon the part *b*, the object of such being to make the shank of wire and deeper in rear of the projection *B* than in front of it.

The grooves of the knitting-machine are usually cut deep enough to take in the doubled shank shown in Fig. 2, the purpose of the in-

crease in the depth of the shank being to keep the needle from tipping or turning over laterally when in operation. With the needle represented in Fig. 2 the part *c* of the shank is liable to become bent out of place or broken off at its heel or bend. The crooked or corrugated shank overcomes these objections, is more easily made and requires less material or stock in its construction, and operates to as good, if not much better, advantage.

I do not confine my invention or improvement to the precise form of corrugations or flexures, as represented in Fig. 1, as the same may be varied more or less without changing the principle or character of my invention.

I do not herein claim the needle made as represented in Fig. 2 of the above-mentioned drawings—that is, as formed with a doubled shank; but

I claim as my invention—

The improved knitting-machine needle, made with a series of flexures or corrugations, *a a a*, in its shank, substantially as represented in Fig. 1 of the aforesaid drawings, and as hereinbefore specified.

WALTER AIKEN.
